GARMENT HANGER

George S. Wilson, Haworth, N. J.

Application October 30, 1945, Serial No. 625,660

5 Claims. (Cl. 223—96)

1

This invention relates to garment hangers and more specifically to hangers for trousers or similar articles.

The primary object of the invention is to provide a novel and improved hanger of the aforementioned character, which, while being of very simple construction so as not to increase unduly the cost of the article is however sturdy and practical in use, and is so arranged as to facilitate the placing of the garment on the hanger and the removal of the garment therefrom, and to insure clamping of the garment in supported position without formation of objectionable wrinkles or creases in the garment material.

Further, it is an object of the invention to provide a hanger which substantially consists of only a pair of elongated members or bars interconnected for relative movement and cooperating to support and clamp the garment, said members being so constructed and arranged that the garment may be placed on the hanger merely by inserting one end thereof between the members. Another object is to provide a pair of members, as aforesaid, adapted to automatically clamp, upon insertion, the garment end therebetween, irrespective of the position of the hanger, said members embodying portions oppositely engaging the garment end to retain the same in clamped condition.

These and other objects will become apparent in the following description of the invention illustrated in the drawings, wherein:

Fig. 1 is a front elevational view of a hanger for trousers and the like, according to the invention.

Fig. 2 is an enlarged end elevational view of the hanger looking in the direction of the arrows 2—2 of Fig. 1, showing the position of the elements of the structure when the hanger is in use.

Fig. 3 is a cross-section through the hanger, on line 3—3 of Fig. 1.

Fig. 4 is a similar cross-section, on line 4—4 of Fig. 1.

Referring now in detail to the drawings, it will be seen that the hanger comprises two associated members or bars, generally indicated at 10 and 11, which cooperate to support and clamp a pair of trousers or like articles placed on the hanger, in the manner hereafter disclosed.

The upper bar 10 consists of an elongated piece or strip of suitable material, preferably of sheet metal, aluminum or the like, of sufficient thickness to provide a rigid structure, which is bent to define a main portion 12 and a further portion 13 extending lengthwise of the bar at an angle to one another, preferably at an angle of about 45°, as shown in Figs. 2 to 4.

Portion 12 is centrally deformed, at its edge remote from portion 13, to provide a further substantially flat portion 14, which in turn is angu-

2

larly offset relative to portion 12 also preferably by about 45°. A suspension hook 16 passing through a hole in said portion 14 is suitably secured to the bar, for instance by means of a retaining head 17 adapted to bear against a washer 18 interposed between a surface of said head and the lower face of the portion 14 of the bar. The opposite ends of the portion 12 are formed with integral ears or lugs 19 projecting therefrom at a right angle to the plane of said portion, in a downward direction when the bars 10 and 11 are assembled as shown in the drawings.

The lower bar 11, which is also made from an elongated piece or strip of the same material as the bar 10 and is slightly shorter than this latter, is likewise bent longitudinally to define a plane main portion 20 and a portion 21 of curved section projecting laterally from the portion 20. This latter portion is also provided at its opposite ends with integrally formed lugs 22 which, in the assembled condition of the hanger, extend upwardly and are pivotally connected to the lugs 19 as by means of rivets 23 or the like.

The bars 10 and 11 are assembled in inverted position relative to one another, that is the respective bent or curved portions 13 and 21 project in opposite directions. The distribution of weight is therefore such that when the hanger is suspended by its hook 16, the bar 11 is caused to rotate relative to the bar 10 to bring the edge of said portion 20 thereof into contact with the opposed edge of portion 13 of bar 10, which latter portion extends then downwardly in substantially vertical position due to the structure of the bar 10 and offset position of the hook associated therewith relative to the longitudinal axis of the bar.

The hanger is also preferably provided with a spring 24 partially wound around one of the rivets 23 and having opposed ends bearing against one of the lugs 22 and the undersurface of the main portion 12 of the bar 10, to normally maintain said portions 20 and 13 of the bars in contact as aforementioned.

It will be apparent from the foregoing description that a garment may be placed in the hanger in the most expeditious manner by placing one end thereof on the bar 11 at the open front of the hanger and angularly displacing the two bars relative to one another to move the portion 13 of the bar 10 away from the portion 20 of the bar 11, in opposition to the spring 24, by a distance sufficient to permit insertion of one end of the garment therebetween. Upon release of the bars, the spring 24 will urge the bars back to their normal position, and therefore the end of the garment will be clamped between the edges of the bar portions 13 and 20, regardless of whether the hanger is then suspended or not. It should be noted that this facilitates considerably the placing of the garment on the hanger and eliminates

the difficulty, generally experience with usual hangers, of maintaining the garment in the proper position thereon when the hanger is not in suspended condition or is moved from one place to another.

When the hanger is suspended by the hook 16, the clamping of the garment is insured independently of the spring 24 because the bar 11 tends to rotate in a direction to bring the edge of the portion 20 thereof toward the edge of the portion 13 of the bar 10 to clamping position, as aforesaid, and the weight of the garment extending downwardly from the portion 21 of the bar 11 at the front of the hanger obviously securely maintains the bar in such clamping position.

A hanger according to the invention may be advantageously used not only with trousers, skirts and the like but also with numerous other articles such as towels, and it is understood that changes and modifications may be made in the structures described and illustrated in the drawings without departing from the spirit of the invention or exceeding the scope of the claims.

I claim:

1. A hanger for trousers comprising an upper bar provided with a suspending hook and having at one side thereof an angularly offset downwardly extending portion, and a lower bar pivotally interconnected with the upper bar and having a first portion extending in underlying relationship to the lower edge of said angularly offset portion of the upper bar and a second portion opposite said first portion with respect to the pivotal connection between the two bars, whereby upon insertion of a pair of trousers between the two bars, the major portion of the trouser weight bears on said second portion of the lower bar, and said first portion of the lower bar swings upwardly to clamp the end of the trousers against said lower edge of said angularly offset portion of the upper bar when the hanger is suspended by said hook.

2. A hanger for trousers comprising an upper bar provided with a suspending hook and having at one side thereof an angularly offset downwardly extending portion, and a lower bar pivotally interconnected with the upper bar and having a first portion extending in underlying relationship to the lower edge of said angularly offset portion of the upper bar and a second portion opposite said first portion with respect to the pivotal connection between the two bars, whereby upon insertion of a pair of trousers between the two bars, the major portion of the trouser weight bears on said second portion of the lower bar, and said first portion of the lower bar swings upwardly to clamp the end of the trousers against said lower edge of said angularly offset portion of the upper bar when the hanger is suspended by said hook, and resilient means for so pivoting the lower bar and so swinging said first portion of the lower bar independently of the weight of the trousers.

3. A hanger for trousers comprising an upper bar provided with a suspending hook and having at one side thereof an angularly offset downwardly extending portion, a lower bar, and pivotally interconnected oppositely extending lugs integral with the ends of said bars, the axis of the pivotal connections of said lugs being in the same vertical plane as said hook, said lower bar having a first portion extending in underlying

relationship to the lower edge of said angularly offset portion of the upper bar and a second portion opposite said first portion with respect to said pivotal connections, whereby upon insertion of a pair of trousers between the two bars, the major portion of the trouser weight bears on said second portion of the lower bar, and said first portion of the lower bar swings upwardly to clamp the end of the trousers against said lower edge of said angularly offset portion of the upper bar when the hanger is suspended by said hook.

5. A hanger for trousers comprising an upper bar provided with a suspending hook and having at one side thereof an angularly offset portion projecting downwardly in substantially vertical position when the bar is suspended by its hook, and a lower bar pivotally interconnected with the upper bar and having a first portion extending in substantially horizontal position underneath the lower edge of said angularly offset portion of the upper bar and a second portion opposite said first portion with respect to the pivotal connection between the two bars, whereby upon

10 insertion of a pair of trousers between the two bars, the major portion of the trouser weight bears on said second portion of the lower bar, and said first portion of the lower bar swings upwardly to clamp the end of the trousers against said lower edge of said angularly offset portion of the upper bar when the hanger is suspended by said hook.

15 20 25 30 35 40 45 50 55 60 65 70 75 80 85 90 95

4. A hanger for trousers comprising an upper bar provided with a suspending hook and having at one side thereof an angularly offset portion projecting downwardly in substantially vertical position when the bar is suspended by its hook, and a lower bar pivotally interconnected with the upper bar and having a first portion extending in substantially horizontal position underneath the lower edge of said angularly offset portion of the upper bar and a second portion opposite said first portion with respect to the pivotal connection between the two bars, whereby upon

insertion of a pair of trousers between the two bars, the major portion of the trouser weight bears on said second portion of the lower bar, and said first portion of the lower bar swings upwardly to clamp the end of the trousers against said lower edge of said angularly offset portion of the upper bar when the hanger is suspended by said hook.

5. A hanger for trousers comprising an upper bar provided with a suspending hook and having at one side thereof an angularly offset portion extending downwardly in substantially vertical position when the bar is suspended by its hook, a lower bar, pivotally connected oppositely extending lugs integral with the ends of said bars, the axis of the pivotal connection of said lugs being in the same vertical plane as said hook, said lower bar having a first portion extending in substantially horizontal position underneath the lower edge of said angularly offset portion of the upper bar and a second portion opposite said first portion with respect to said pivotal connections, whereby upon insertion of a pair of trousers between the two bars, the major portion of the trouser weight bears on said second portion of the lower bar, and said first portion of the lower bar swings upwardly to clamp the end of the trousers against said lower edge of said angularly offset portion of the upper bar when the hanger is suspended by said hook, and resilient means for so pivoting the lower bar and so swinging said first portion of the lower bar to clamp the trousers independently of the weight thereof.
